COMBINED MAIL BOX AND LAMP

Orville Wright, Louisville, Ky.

Application April 21, 1958, Serial No. 50,548

Term of patent 14 years

(Cl. D74—9)

The undisclosed back is plain and unornamented and presents a substantially similar appearance as the front except for the letter slot and the numerals.

I claim:

The ornamental design for a combined mail box and lamp, as shown and described.
